UNITED STATES PATENT OFFICE

HARRY T. KINGSBURY, OF KEENE, NEW HAMPSHIRE, ASSIGNOR TO KINGSBURY MFG. COMPANY, OF KEENE, NEW HAMPSHIRE, A CORPORATION OF NEW HAMPSHIRE

CHECK DISPENSER

Application filed August 29, 1931. Serial No. 560,222.

The present invention relates to improvements in check dispensing machines of the type in which a tape comprising the checks is successively delivered, measured and severed when a check is withdrawn from the machine.

One of the features of the present invention is the provision of means whereby the check which is exposed for withdrawal has already been severed from the tape prior to the time at which it is presented for withdrawal.

Another feature of the machine is the provision of means whereby one portion of the tape is advanced more rapidly than another portion, and means are provided for severing the tape at the fold formed by the differential advancements.

Still another feature of the invention is the provision of means whereby the tape and its advancing mechanism cooperate with a finger whereby the finger is caused to sever the tape at a predetermined point and at a predetermined time during the advancement of the tape.

Another feature of the invention is the provision of a tape for cooperating with dispensing machine elements whereby the tape is definitely and positively severed by a tearing operation in such a manner that the remaining portion of the tape is presented regularly for advancement, without danger of jamming or blocking the machine parts.

With these and other features in view as will appear in the following specification and claims, an illustrative form of the construction of a machine is set forth on the accompanying drawings in which:

Figure 1 is a plan view of the machine.

Fig. 2 is a side elevation of the same.

Fig. 3 is a vertical section through the same substantially on line 3—3 of Fig. 6.

Fig. 4 is a similar section, with the parts in a different operative position.

Fig. 5 is likewise a similar view, with the parts in a still different position.

Fig. 6 is a transverse vertical sectional view substantially on the line 6—6 of Fig. 3.

Fig. 7 is a perspective view showing the folding of the tape and the engagement of

the tearing finger therewith just prior to severing.

Fig. 8 is a view showing a portion of the tape including the notches at which severing is effected.

Fig. 9 is a view of one check as severed from the tape.

In these drawings the base 10 has an upright 11 thereon to receive the shaft 12 on which is mounted a supply roll 13 of tape.

Likewise mounted on this base are side plates 14, 15 which support the various shafts for the feeding system. Extending transversely through the machine is the main gear shaft 16 having a large gear 17 at one end thereof in mesh with the small gear 18 mounted on a lower shaft 19 and having also fixed thereto a twin gear 20 which meshes with the upper twin gear 21 on an upper feed shaft 22. Likewise meshing with the main gear 17 is a lower gear 23 on the lower delivery shaft 24. The delivery gear 23 meshes with the delivery gear 25 on the upper delivery shaft 26.

On the shafts 19 and 22, between the plates 14, 15, are provided the pairs of feed rollers 27, 28 which preferably are of soft base material such as rubber in order to afford a proper frictional grip upon the tape. Likewise, on the shafts 24, 26 are provided friction rolls 29, 30 which likewise engage the check as it is being delivered.

Between the rolls 27, 28 and 29, 30 is provided a lower apron or guide piece 31 which is bent downwardly at the sides and secured to the side plates 14, 15 as by the screws 32. Above this apron 31 is a second guide apron 33 which is spaced from the first apron by a distance which permits the passage of the overlapped portions of the tape and the check severed from the tape. This upper apron 33 is likewise bent at its sides and fits on top of the side plates 14, 15 and is secured thereto by screws 34. At the end of the plate 33 which is first encountered by the tape are provided a pair of fingers 35 (Fig. 1) for engagement in slots of the tape as will be described in detail hereinafter.

At the feeding side of the rolls 27, 28 is provided a guide member 40 which likewise is secured by screws 41 to the side plates 14, 15

(Fig. 1) and serves to receive and guide the tape in its travel through the machine and to prevent it from being forced downwardly. This member is provided with a notch 42 for 5 the reception of the tearing arm as will be described hereinafter. A top plate 43 is secured to the extension of plate 40 by screws 44 and serves in cooperation with plate 40 to hold the tape in proper rectilinear position as it is being delivered into the feeding and discharge rolls.

The side plates 14, 15 are preferably held spaced by the bolts 45 and collars 46 in the usual manner.

15 Loosely mounted on the shaft 22 of the upper feed rolls is a metal trough-like member 50 having formed integral therewith an arcuately bent tearing arm 51. To this member 50 is secured by a screw 52 the clamp piece 53 so that between the members 50 and 53 a frictional engagement is produced with respect to the tape 22 so that the tearing arm 51 is carried in rotation on the shaft 22 when not opposed by a force sufficient to cause the relative rotation of these members.

The ticket strip or tape which is particularly adapted to be employed with this machine is shown in Figs. 8 and 9 in which the individual tickets A, B are connected in the 30 tape by the web pieces 70, while the slots 71 are provided in transverse alignment and longitudinally spaced from but in alignment with the webs 70. This ticket strip or tape of checks is disclosed and claimed in my co-pending application Serial No. 670,544, filed 35 May 11, 1933.

In operation, the ticket strip or tape comprising pluralities of tickets joined as shown in Fig. 8 is fed between the guide plates 40, 40 43 (Figs. 1 and 2) into position between the feed rollers 27, 28. The master gear 17 is then rotated in a counterclockwise direction (Fig. 2) by hand so that it drives the small gear 18 and therewith the twin gears 20, 21 and the rollers 27, 28 which engage with the tape adjacent its edges and cause it to be fed forward toward the right in Figs. 1 and 2. The advancing end of the ticket tape normally passes of itself between the fingers 35 and 45 the lower plate 31, which as shown in Fig. 3 has a downwardly bent lip 31^a to guide the advancing end. The continued rotation of the master gear 17 causes the advancement of the ticket strip until it encounters the delivery rolls 29, 30. The rolls 29, 30, are likewise driven through their intermeshing gears 23, 25 from the master gear 17 but at a lesser peripheral speed than the rollers 27, 28. Hence the advancement of the tape is delayed, 50 and the tape tends to double up and overlap between the rollers and rolls.

During the rotation of the shaft 22, the arcuate severing arm 51 has been moved in the counterclockwise direction with this 60 shaft until its extreme end has come to rest

against the upper surface of the tape, in which position the arm is held at a standstill until the central aperture 72 (Fig. 8) between two individual tickets or checks comes beneath the arm 51. At this time 70 the arm 51 can continue in its counterclockwise movement with the shaft 22. The arm swings from the full line position shown in Fig. 3 through the dotted line position there-in and ultimately assumes the position shown 75 in Fig. 4 in which it has engaged with the foremost ticket or check in the same transverse line as the slots 71. Owing to the engagement of the foremost ticket with the rolls 29, 30, this foremost ticket is now delayed, while the next succeeding ticket is advanced and by the action of the arm 51 in raising the rear end of the foremost ticket, the next ticket is caused to move forward beneath the foremost ticket, so that the position shown in Fig. 4 is attained.

This upward bending movement of the rear end of the foremost ticket however brings the slots 71 opposite the ends of the fingers 35 so that these fingers tend to enter the slots, being assisted in this by the upward bending of the rear edges of these slots (Fig. 7). As the tickets are continuously fed forward, the fingers 35 penetrate into the slots and cause a tearing of the material of the tape at the points along the dotted lines 75 in Fig. 8 by reason of the traction through the foremost ticket A, and therewith also the fingers 35 cause the tabs 70^a (Fig. 9) formed by the webs 70 and the portions lying within the respective pairs of dotted lines 75 to be folded backward over the top of the succeeding ticket to which they are integrally joined, so that they do not project laterally to obstruct or impede the properly guided forward movement of the ticket B, and hence the foremost ticket has been turned and separated from the next following ticket.

A slight further movement of the master gear 17 causes the advancing edge of this 110 foremost ticket to project so that it may be grasped between the thumb and finger (Fig. 3). Upon pulling this foremost ticket A forward, the above operations are repeated and the next succeeding ticket is thus detached from the third ticket of the original strip and itself moved into the position shown for the ticket A in Fig. 8. In other words, by pulling the successive tickets as they are presented at the position of ticket A in Fig. 3, the next ticket is prepared for delivery by severing it from the ticket next following. Owing however to the greater rate of advancement given the tape by the feeding rollers 27, 28, the tape is fed forward into overlapping relationship with the detached ticket A, so that the next succeeding ticket B is engaged with the delivery rolls 29, 30 before the foremost ticket A has been freed therefrom (Fig. 4). Thus, when the ma- 120 125 130

chine is at a standstill ready for delivery of a ticket, this ticket has already been detached from the tape of which it has formed a part: and the operation of removing this 5 foremost and projecting ticket results in the detachment of another ticket and its delivery in a position ready for grasping.

The forward movement of the foremost ticket A (Fig. 7) disengages it from above 10 the severing arm 51 so that this arm is now free again to move in a counterclockwise direction with shaft 22. It will particularly be noted that by reason of the frictional relationship of the arm 51 with shaft 22, the rollers 15 28 need not be accurately dimensioned as to their periphery with respect to the length of the individual tickets, so long as the severing arm 51 is brought down against the ticket strip not later than the time at 20 which the hole 72 is presented opposite the path of travel of this arm.

It will be understood that normally the machine is provided with an enclosing casing 100 as indicated in dotted lines in Fig. 25 3, so that the machine may be placed on a restaurant counter, for example, and the patrons have access only to the single individual ticket which is offered through the slot 101 in the casing 100. The casing has 30 a removable portion such as the door 102 mounted on the ticket 103 by which access may be gained to the mechanism for the replacement of the supply roll 13 and for the initiation of delivery of tickets from the new 35 tape.

Obviously, the invention is not limited solely to the form of execution shown but may be modified in many ways within the scope of the appended claims.

40 What is claimed:

1. A check dispensing apparatus including feeding and delivery means for a tape, and positive motion transmitting devices connecting said means so that they are operated 45 continuously together at different speeds, whereby the tape is caused to be fed faster than it is delivered from the apparatus.

2. A check dispensing apparatus including feeding and delivery rolls for a tape, and positive motion transmitting devices connecting said means so that they are operated continuously together at different speeds, whereby the tape is caused to be fed faster than it is delivered from the apparatus.

55 3. A check dispensing apparatus including feeding rolls and delivery rolls and means to guide the tape between said rolls, and means whereby said rolls are operated positively together at different speeds so that the 60 tape is caused to kink and overlap between said rolls.

4. A check dispensing apparatus including feeding rolls and delivery rolls and means to guide the tape between said rolls, means 65 whereby said rolls are operated at different

speeds so that the tape is caused to kink and overlap between said rolls, and means for severing the tape at the kink.

5. In a check dispensing apparatus, a pair of delivery rolls engaged with the check to 70 be dispensed so that the rolls are rotated as the check is withdrawn, feeding rollers engaged with the tape from which the checks are to be severed, and means connecting said rolls whereby the delivery rolls drive the 75 feeding rolls at a greater peripheral rate so that the tape is caused to kink between said delivery and feeding rolls.

6. An apparatus as in claim 5, including 80 guide means for the tape between said rolls and means engageable with an aperture in the tape for detaining a portion of the tape at the kink whereby a pull on the end of the tape will cause a tearing and severing of the 85 end check from the tape.

7. A check dispensing apparatus comprising delivery rolls and feed rolls, means connecting and causing said rolls to move at different peripheral speeds whereby to cause 90 kinking of a tape engaged with said feed rolls, guides to support the tape between said delivery and feed rolls, and tearing means engageable with the tape at the kinked portion thereof for severing the tape.

8. A check dispensing apparatus employing 95 a tape of checks having apertures therein, delivery and feed rolls engaged with the checks, guides for supporting the tape between said rolls and including fingers to enter said apertures, and means for moving the tape out of its plane into engagement with 100 said fingers.

9. A check dispensing apparatus comprising 105 delivery rolls and feed rolls engageable with a tape of checks, means for connecting said rolls for differential peripheral movement whereby the tape is fed past said feeding rolls more rapidly than it is delivered from said delivery rolls so that a kink is formed therein, and means for severing the 110 tape prior to its withdrawal from said delivery rolls whereby the greater speed of the feeding rolls will cause a succeeding check to enter between said delivery rolls before the 115 end check is removed therefrom.

10. A check dispensing apparatus including pairs of driving and feed rolls for engagement with a tape of checks, a main shaft, and intermeshing gears on the rolls and shaft so that the same move in unison, the speed 120 ratio between the delivery rolls and said shaft being less than the speed ratio between said feed rolls and said shaft.

11. A check dispensing apparatus comprising 125 a pair of delivery rolls, a pair of feeding rolls, intermeshing gears on each of said pairs of rolls, a main gear in driving relationship with both said pairs of rolls, the gear ratio between said main gear and said delivery gears being less than the ratio be 130

tween said main gear and said feeding rolls.

12. A check dispensing apparatus including feed rolls to engage a tape of checks, delivery rolls to engage an end check, said feed rolls being driven at a greater peripheral speed than said delivery rolls, and tape guides located between said rolls and including means to engage and detain a part of the tape, whereby a pull on a check projecting from said delivery rolls will cause a tearing of the tape between said rolls and an overlapping of the end of said tape past the torn end of a check.

13. A check dispensing apparatus including a pair of delivery rolls and a pair of feed rolls, means for connecting said delivery rolls to said feed rolls whereby the feed rolls are driven at a greater peripheral speed than said delivery rolls, tape guide means between said rolls including means to engage a portion of the tape which is kinked because of the differential movement of said rolls, and to sever the end check from the tape, said guides conducting the end of the tape to the delivery rolls whereby the withdrawal of a check from the delivery rolls will cause the tape to be advanced and severed and the next succeeding and severed check to be delivered between said delivery rolls before the check being withdrawn is separated from said delivery rolls.

14. A check dispensing apparatus including feeding and delivery means for a tape, devices whereby said feeding and delivery means are operated at different speeds so that the tape is caused to be fed faster than it is delivered from the apparatus, and to form a kink between said feeding and delivery means, and a finger movable with the feeding means for determining the point of the kink.

15. In a check dispensing apparatus, a pair of rollers engaging a tape of checks for feeding the same, means for causing the tape to kink, and a finger frictionally mounted on the shaft of one of said rollers whereby to be rotated therewith and operating to determine the point of the kink.

16. A check dispensing apparatus including feeding and delivery means for a tape, motion-transmitting devices for driving said means at different speeds whereby the tape is caused to be fed faster than it is delivered from the apparatus, and a tape guide between said means for causing the tape to kink into overlapping condition owing to the differential feeding and discharge thereof.

In testimony whereof, I affix my signature.

HARRY T. KINGSBURY.
